CLAIM

The ornamental design for a tote bag, as shown and described.

DESCRIPTION

FIG. 1 is a front top perspective view of a tote bag showing my new design.

FIG. 2 is a rear top perspective view thereof;

FIG. 3 is a front plan view thereof;

FIG. 4 is a rear plan view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict portions of the tote bag that form no part of the claimed design.

1 Claim, 6 Drawing Sheets
